UNITED STATES PATENT OFFICE.

EDMUND C. MORGAN, OF CHICAGO, ILLINOIS; OLIVE EUGENIE MORGAN EXECUTRIX
OF SAID EDMUND C. MORGAN, DECEASED.

MINING MACHINE.

Application filed May 22, 1916. Serial No. 99,015.

To all whom it may concern:

Be it known that I, EDMUND C. MORGAN, a citizen of the United States, residing at Chicago, in the county of Cook and State 5 of Illinois, have invented certain new and useful Improvements in Mining Machines, of which the following is a specification.

This invention relates to machines for mining coal and similar material, and has 10 for its object the provision of a machine of the class mentioned which shall be of improved construction and more efficient and economical in operation than machines of the same character heretofore known. The 15 invention is exemplified by the combination and arrangement of parts shown in the accompanying drawings and described in the following specification, and it is more particularly pointed out in the appended claims.

20 In the drawings—Fig. 1 is a side elevation of a mining machine embodying the present invention; Fig. 2 is a top plan view of the machine shown in Fig. 1; Fig. 3 is a vertical sectional view on line 3—3 of Fig. 2; Fig. 4 is an elevational view of the machine looking at the side opposite that shown in Fig. 1, and showing the machine in a lowered position; Fig. 5 is a fragmentary rear elevational view showing the position in 25 which the machine rests on the mine floor, and other features; Fig. 6 is a fragmentary horizontal sectional view on line 6—6 of Fig. 3; Fig. 7 is a fragmentary vertical sectional view on line 7—7 of Fig. 6; Fig. 8 is 30 a fragmentary view showing a detail of construction; Fig. 9 is a fragmentary horizontal sectional view on line 9—9 of Fig. 3; Fig. 10 is a vertical sectional view on line 35 10—10 of Fig. 2; Fig. 11 is a fragmentary vertical sectional view on line 11—11 of Fig. 2; Fig. 12 is a fragmentary vertical sectional view on line 12—12 of Fig. 9; Fig. 40 pinion 50 secured to the armature shaft of a motor 51. When the clutch lever 48 is operated, the motor 51 will be connected through the gearing described with the 5 worm 41 and the pinions 39 to rotate the pinions in mesh with the rack teeth 28, and thus adjust the position of the mining machine frame.

The main base plate 35 constitutes a bed 10 plate for a conveyer chain 55 having a plurality of horizontal flights 56 which travel over the plate 35. Extending longitudinally along the center of the plate 35 is an upstanding ridge or guide 57 about which the 15 chain 55 travels, as best shown in Figs. 2 and 10. The chain 55 is driven by a sprocket wheel 58 journalled in the plate 35 at the rear end thereof, as shown in Fig. 3 and connected with a worm wheel 59 meshing 20 with a worm 60 carried on the shaft 61. The shaft 61 is provided with a bevelled pinion 62 meshing with a corresponding pinion 63 secured to a transverse shaft 64. The shaft 64 carries a clutch 65 arranged to 25 be operated by a clutch operating handle 66 and arranged to connect with a clutch face 67 carried by a stud shaft 68. The stud shaft 68 is connected by pinions 69 and 70 (Fig. 1), vertical shaft 61 and bevelled pinions 72 and 73, with the shaft 46. When 30 the handle 66 is operated to connect the shafts 64 and 68, the conveyer 55 will be driven through the mechanism described by means of the motor 51 operating through 35 the shaft 46.

The run of the conveyer shown at the right in Fig. 10, and at the bottom in Fig. 2, is the carrying run and travels toward the rear of the machine. To protect the rear 40 run of the conveyer, a casting 75 is provided which rests upon the chain guide 57 at one side and upon an upstanding flange 76 at the outer edge of the plate 35. The casting 75, as shown in Fig. 10, slopes upwardly 45 from the central portion of the conveyer trough and is provided with an upstanding wall 77 at the outer edge of the trough. A corresponding wall 78 projects upwardly 50 from the edge of the base plate 35 on the side of the conveyer trough adjacent the carrying run of the chain. By this arrangement it will be seen that material in the conveyer trough, formed by the plate 35 and casting 75, will tend to gravitate to the 55 side of the conveyer trough in which the carrying run of the chain travels and the return run of the chain will be entirely protected from contact with material in the conveyer trough. The casting 75 is provided with supporting brackets 79 for supporting the casting in proper position. The wall 77, as shown in Fig. 2, is curved inwardly 60 toward the center of the conveyer trough at the forward end for a purpose that will later appear. The casting 75 is

continued at its bottom portion to form a base plate 80 on which the motor 51 is mounted.

The main base plate 35 at the forward end is extended laterally to form the support 70 for the cutter head. The laterally extended portion of the plate 35 is provided centrally with a bearing 81 in which an upright shaft 82 is journalled for rotation. The upper end of the shaft 82 is journalled in a bearing 83 carried at the end of an arm 84 secured to an upright bracket 85 formed integral with the plate 80 of the casting 75 (Figs. 1 and 10). A spacer 86 is arranged 75 between the lower surface of the plate 80 and the upper surface of the main base plate 35 to hold the plate 80 in proper position relative to the operating parts of the machine and in spaced relation with the base plate 35 to permit operation of the 80 chain between the base plate and the supporting plate 80. The shaft 82 is provided with a ratchet wheel 87 rigidly secured to the shaft at a point just below the bearing 83. A lever 88 is pivotally mounted at 85 on the lower side of the arm 84 and carries a detent 90 arranged to cooperate with the teeth 91 of the ratchet wheel 87 (see also Fig. 2). By means of the detent 90, the ratchet wheel 87 and shaft 82 may be held 90 from rotation in the bearings 81 and 83. The lower end of the shaft 82 has a spur gear 92 secured thereto, the upper surface 95 of the spur gear being provided with a circular hub 93 on which is journalled for rotation 100 the bottom plate 94 of the cutter head. The plate 94 forms a part of a skeleton framework or casting on which the operating mechanism for the cutter chain is mounted. The casting is cylindrical in 105 shape and is provided with an upright plate 95 at the rear portion thereof and a heavy upright supporting bar or standard 96 at the forward side thereof, shown best in Figs. 3 and 6. A cover plate 97 is provided 110 for the casting secured in place by lag screws 98 (Fig. 2) and provided with covered openings 100 through which access may be had to the enclosed machinery. The cutter head casting is provided at its lower 115 edge with a peripheral flange 101 (Fig. 3) which supports for rotation about the cutter head a hollow cylindrical drum 102. The drum 102 is provided with rack teeth 103 extending around the outer portion thereof, as shown in Figs. 1, 2 and 3, by means of which the drum may be rotated relative to the cutter head. The outer surface of the cylindrical drum is provided with corrugations 104 for a purpose to be explained. A 120 motor 105 is mounted on the plate 94 and is held in place by lag screws 106. The armature shaft of the motor carries a pinion 107 which meshes with a gear 108 secured to a 125 shaft 109 mounted in bearings 110 (Fig. 6) 130

carried by a bracket 111 supported on the upright portion 96 of the main cutter head casting. The shaft 109 carries a sprocket wheel 112 over which a cutter chain 113 passes and by means of which the cutter chain is driven. The cutter chain, as shown in Fig. 3, is guided over the upper and lower ends of the upright portion 96 of the cutter head casting, and thence passes into cooperative relation with a loop-shaped cutter chain guide 115 which is held rigidly connected with the member 96 by lag screws 116.

As shown in Fig. 1, when the clutch 180 is in released position, the cylinder with the corrugations 104 thereon is free to rotate by reason of the nature of the gearing connections. Therefore the friction between the drum and the corrugated cylinder tends to hold the follower 175 in the position shown in Fig. 2. As soon as the core has been completely cut, the clutch 180 may be thrown in by means of the lever 181, as shown in Fig. 1, and the follower 175 rotated in a clockwise direction as viewed in Fig. 2, together with the corrugated cylinder, independently of the operation of the cutting mechanism because the follower can be moved through the cutter frame. However the core material may be moved against the corrugated cylinder, the latter will assist by frictional engagement with the material to move the latter toward loading position. In other words, after the core has been cut and while it is resting on the arcuate platform, it may be moved against the corrugated cylinder in any desired manner, and when this is done the corrugations will assist the platform in loading material.

The shaft 109 carries at the end opposite the gear 108, a worm 117 (Fig. 6) arranged to be clutched to the shaft by a clutch 118 operated by a lever 119 positioned in a depression 120 (Fig. 2) in the cutter head top plate 97. The worm 117 is arranged to drive a train of gearing best shown in Fig. 7. A bearing plate 121 is secured by bolts 122, (Fig. 6) to the inner side of the periphery of the cutter head casting and is held in spaced relation with the bottom plate 94 of the casting. An upright shaft 123 is journalled in the bearing member 121 and carries at its lower end a pinion 124 having an upwardly extending sleeve 125 which passes through the base plate 94 and is journalled for rotation therein. The pinion 124 is free to rotate on the shaft 123 and the sleeve 125 has a gear wheel 126 secured through and keyed to rotate with the pinion 124. A second upright shaft 127 is journalled in the bearing member 121 and the base plate 94 and carries gear wheels 128 and 129 rigidly secured thereto. The gear wheel 129 meshes with the gear 126 and the gear wheel 128 meshes with a pinion 130 formed integral with a worm wheel 131

which meshes with the worm 117. By this arrangement, a reduction gear train is provided by means of which the pinion 124 is driven from the worm 117 at a greatly reduced speed. The pinion 124 meshes with the gear 92 carried at the lower end of the shaft 82. It will be apparent that when the clutch 118 connects the shaft 109 with the motor 105, the pinion 124 will be caused to travel around the periphery of the gear 92 and thus rotate the cutter head about the shaft 82, provided the shaft is held from rotation by means of the detent 90. By this means the cutter head is rotated to feed the cutter chain 113 and frame 115 through an arcuate path to sever a crescent-shaped section of material indicated at 132 (Fig. 2) from the face of a mine vein.

The inward run of the cutter chain 113, as shown in Fig. 3, extends over the forward end of the conveyer chain 55, so that the cuttings of the chain 113 are drawn inwardly and discharged into position to be carried back by the flights 56 over the main frame bed plate. The forward end of the chain 55 passes around an idler sprocket 135 journalled on the shaft 82 just below the gear wheel 92. The sprocket 135 and the front portion of the conveyer chain rest on a plate 136 (Figs. 3 and 9) which is provided with an upstanding central portion 137 which acts as a guide for the conveyer chain. The plate 136 is secured by lag screws 138 (Fig. 3) to the main frame bed plate 35. The plate 136 is provided at its forward edge with an upstanding flange 192 which retains the cuttings discharged by the chain cutter 113 on the front portion of the plate 136, and prevents their being pushed off by the centrifugal action of the flights 56.

As shown in Figs. 3, 9, 11 and 12, the main frame bed plate 35 is provided at its forward end with a circumferential portion 140 which is offset downwardly and supports an adjustable extension plate 141. The rear portion of the plate 141 is provided with a series of openings 142 which mesh with the teeth of gear segments 143 (Fig. 8) carried on a shaft 144 which is provided with an operating handle 145 (Fig. 9) by means of which the gear segments may be rotated. By this device, the extension plate 141 may be forced forwardly into contact with the face of the material, as shown in Fig. 3, to make a close connection between the front end of the machine platform and the face of the mine wall, to prevent escape of any small portions of material that may be severed during a cutting operation. The rear edge of the plate 141 on the side of the machine over which the severed coal is transferred, extends backwardly into a recess 146 formed in the front edge of the main frame bed plate 35, as shown in Figs. 9 and 12. A pro-

jecting ledge 147 overhangs the recess 146 and extends over the rear edge of the plate 141. The forward portion of the ledge 147 is bevelled, as indicated at 148, so that material will pass freely from the plate 141 onto the plate 35. A series of openings, 149, extend through the downwardly offset portion 140 of the bed plate 35 in the rear of the plate 141, to permit escape of any particles of material that may be imprisoned behind the plate 141. As will be seen from Figs. 11 and 12, the upper surface of the plate 141 is lower than the upper surface of the main portion of the bed plate 35, and the plate 136 over which the forward end of the chain 55 passes. This provides a depression or slideway between the front edge of the plate 35 and the periphery of the plate 136. In this slideway a follower or receiving table 150 (Figs. 2, 6 and 9) is arranged to slide. The receiving table 150 is arcuate in shape and has its forward end connected by a hinge 151 to a rearwardly extending portion 152 of the lower arm of the cutter frame 115. As the cutter frame is moved to sever a section of material from the mine wall, the receiving plate 150 is drawn in the rear of the cutter frame into the lower kerf formed thereby, the receiving plate being of sufficient length to extend from the rear of the cutter frame to the forward edge of the plate 35, when the cutter frame has moved to the extreme limit in a cutting operation. A pivoted stop 155 is hinged at 156 and 157 to the upstanding chain guides 137 and 57 respectively, as shown best in Figs. 9 and 11. This stop bridges the space between the front end of the guide 57 and the rear end of the guide 137, and prevents coal from being carried beneath the casting 75. The pivoted stop is arranged to swing upwardly into the recess between the two runs of the chain 55, and to permit the passage of the receiving table 150 beneath the chain when the table is forced backwardly by the return movement of the cutter frame. The rear edge of the table 150 is bevelled at 158 so that it will pass easily beneath the edge of the pivoted stop 155, automatically forcing the stop upwardly out of its way. Connected with the rear edge of the upright arm of the cutter frame 115, as shown in Figs. 2, 6 and 8, by means of a hinge connection 159, is a belt or apron 160 arranged to be drawn into the kerf formed by the upright arm of the cutter frame when the cutter head is rotated during a severing operation. The rear end of the apron 160 is secured to a drum 161 carried by brackets 162 secured to the wall 78 (Fig. 4) of the main frame 35 in the rear of the cutter head. The drum 161 is provided with a bevelled gear 163 at its lower end which meshes with a pinion 164 carried on a shaft 165. The shaft 165 is provided with a clutch 166 (see

Fig. 2) by means of which it may be operatively connected with an alined shaft 167 (see also Fig. 1), provided with a pinion 168 meshing with a pinion 169 carried on an upright shaft in a bearing 170 and provided with a worm wheel 171 at the upper end thereof. The worm wheel 171 meshes with the worm 172 carried by the shaft 46. By this train of gearing, the drum 161 may be connected with the motor 51 to wind the belt 160 on the drum. The shaft 165 is provided with a friction brake 173 (Fig. 3) arranged to be operated by a lever 174 (Fig. 1) by means of which the drum 161 may be held from rotation.

It is noted that the lever 174 is connected through the lower transverse shaft 193 to a brake lever 194, as shown in Figs. 13 and 14. The rock shaft 193 journaled in the bracket 195 is keyed not only to the operating lever 174 but also to the brake lever 194. As shown in Fig. 13, a brake band 196 extends around the pulley 173 and is connected at its ends to the ends of the lever 194 or to the outer end of the lever 194 at one end and to a projecting portion of the shaft 193 at its other end, as shown in Fig. 14. Therefore, when the lever 174 is moved to one side or the other, the brake band 196 will be brought into firm frictional engagement with the pulley 173 which is keyed to the transverse shaft 165. If the drum is thus restrained during the forward movement of the cutter head, it will be apparent that the apron 160 will be drawn taut, thus causing a portion of the crescent-shaped section of material 132 to be broken from its connection with the mine wall. In this way the material may be broken up if desired during the cutting operation.

To assist in forcing the coal from the position it occupies when disconnected from the mine vein, a follower 175 is secured to the outer portion of the hollow drum 102, as shown in Figs. 1 and 2, and may be rotated with the drum 102 to force the material from the severed position. The rotation of the drum 102 and the follower 175 is accomplished by means of the teeth 103 which mesh with a pinion 176 carried on an upright shaft 177. The shaft 177 is provided with a gear 178 meshing with a pinion 179 carried on the shaft 46 which is driven by the motor 51, as shown in Fig. 2. The gear 178 may be secured for rotation with the shaft 177 by a clutch 180 having (Fig. 1) an operating handle 181. In this way, the drum 102 and the follower 175 may be driven by the motor 51 to rotate about the cutter head.

For adjusting the position of the machine in the mine chamber, the main base plate 20 has a motor 185 (Fig. 3) mounted thereon which is connected by worm gearing to a drum 186 on which a pair of cables 187

100

105

110

115

120

125

130

and 188 are wound. The cables 187 and 188 pass over pulleys 189 at opposite edges of the machine frame, and are secured at their ends to anchors 190 which may be located 5 in proper position in the mine chamber to accomplish desired movements of the machine frame.

During operation the base plate 20 rests on the floor of the mine chamber, as shown 10 in Fig. 5. Because of the nature of the cut made by the loop cutter, the floor of the chamber will be lower at its center than it is at the sides, hence the central portion 15 of the frame will be spaced some distance from the floor of the mine chamber. At the outer edges of the frame the ridges formed by the series of cuts will be somewhat broken down, as indicated at 191 in Fig. 5, by the weight of the machine. When 20 a cut is about to be made, the machine will be moved into position with the forward end of the main base plate 35 adjacent the surface formed by the last preceding cut. If 25 a thick vein is to be operated, the pivotal support 37 will be adjusted into an elevated position, so that the cutter head may be swung to an extreme upper position, as indicated in Fig. 1. If a comparatively thin vein, like that shown in full lines in 30 Fig. 3, is to be worked, the pivotal support 37 will be adjusted to a lower position. In making these adjustments jacks may be used to change the position of the machine frame as found necessary, or the adjustment may 35 be made by the use of the machine's own motor. This would be accomplished by causing the cutter head to rest upon the supporting surface, as shown in Fig. 4. When this is done, the bolt 31 may be removed and the motor then operated to rotate the pinion 39 in contact with the rack segment 27. This rotation will tend to shift 40 the position of the rack about the pivot 26, raising or lowering the pivot 37, depending upon the direction of rotation of the motor and also shifting the lower end of the rack 45 segment 27 relative to the openings 32. By this operation any desired adjustment of the pivot 37 may be accomplished. Before a 50 cut is started, the extension plate 141 is moved forwardly into contact with the mine wall. The upper cut is preferably made first and in starting this cut the cutter frame 115 will be placed in its extreme retracted 55 position, that is rotated as far as possible in a clockwise direction, as viewed in Fig. 2. In this position the end of the receiving 60 table 150 will extend beneath the overhanging plate 80 (Fig. 1) as far as necessary to permit the cutter frame to reach its starting position. The apron 160 will be wound upon the drum 161 and the follower 175 will occupy the position shown in Fig. 2. During the forward movement of the cutter 65 frame, the drum 161 will be permitted to

rotate freely so that the apron 160 may be drawn into the kerf formed by the cutter chain. When a cut has been completed, the detent 90 will be moved out of contact with the ratchet 87 and the entire cutter head 70 will then be free to move. The return movement is accomplished by rotating the drum 161 to exert tension on the apron 160. At the same time the follower 175 is driven through the pinion 176 and the associated 75 gearing, and in this way the table 150, the apron 160 and the follower 175 will all co-operate to force the section of severed material backwardly into position to be transferred by the conveyer flights 56 which are 80 simultaneously driven to discharge the material at the rear end of the machine. A suitable car or other transporting device, receives the material and transfers it to the mouth of the mine. 85

I claim:

1. A mining and loading machine comprising a supporting frame, means mounted thereon for cutting a U-shaped kerf in a mine wall in a general horizontal direction, a framework adjustable to an elevated position to support said cutting means for cutting the kerf at the roof in the plane of the roof of the mine chamber, conveyer mechanism in position for receiving the material as it is dislodged by said cutting means, and means for operating said conveyer mechanism to effect the transfer of the dislodged material rearwardly toward loading position. 95

2. In a mining machine, means for forming a kerf in a mine vein, a platform movable into a portion of said kerf for receiving material as it is severed from its native position, and an apron arranged to be 105 moved into another portion of said kerf.

3. In a mining machine, means for severing a section of material from a mine vein, a receiving platform attached to said severing means and movable therewith, and an apron secured to said severing means and movable into the kerf formed thereby. 110

4. In a mining machine, a loop cutter, means for moving said cutter to sever a section of material from a mine vein, a receiving platform secured to said cutter and movable therewith into position beneath the severed material, and an apron secured to said cutter and movable with said cutter into the kerf formed thereby. 115

5. In a mining machine, a loop cutter, means for moving said cutter to sever a section of material from a mine vein, a receiving platform for the severed material secured to the horizontal portion of said cutter, and an apron secured to the upright portion of said cutter and movable into the kerf formed thereby. 125

6. In a mining machine, a loop cutter, means for rotating said cutter to sever a 130

section of material from a mine vein, an arcuate receiving platform secured to said cutter and movable therewith into position beneath the material severed by said cutter, 5 and a flexible apron secured to said cutter and movable into the kerf formed thereby.

7. In a mining machine, a loop cutter, a receiving platform secured to said cutter and movable into position beneath the material severed by said cutter, an apron secured to said cutter and movable into the kerf formed thereby, and means for exerting tension on said apron to remove the material severed by said cutter from its native position.

8. In a mining machine, a loop cutter, a receiving platform secured to said cutter, an apron secured to said cutter, and means for exerting tension on said apron to move 20 the material severed by said cutter from the position it occupies when severed.

9. In a mining machine, the combination with kerf-cutting mechanism for cutting an upright kerf and a kerf extending in a general horizontal direction, of means for operating said kerf-cutting mechanism, means movable into the horizontal kerf for receiving the cut material, separate means movable along the upright kerf, and mechanism 30 for moving said separate means relatively to said receiving means to break the cut material while conveying it to said receiving means.

10. In a mining machine, a severing device having means for forming a kerf having a substantially horizontal portion and an upright portion, a receiving platform secured to said severing device and movable therewith into the horizontal portion of said 40 kerf, and flexible means secured to said cutter for moving said cutter and receiving table to transfer the material severed by said cutter from its native position.

11. In a mining machine, a severing device arranged to form a kerf having a substantially horizontal portion and an upright portion, a receiving table secured to said severing device and movable therewith into the horizontal portion of said kerf, a flexible apron secured to said severing device and movable therewith into the upright portion of said kerf, and means for exerting 50 tension on said apron to withdraw said severing device and receiving platform from the position into which it is moved while severing material from a mine vein.

12. In a mining machine, a loop cutter, means for rotating said cutter about an upright axis to sever a section of material from a mine vein, a receiving platform secured to said cutter and movable therewith into position beneath the material severed thereby, a flexible apron secured to said cutter and movable therewith into a position 60 adjacent the upright side of the material

severed by said cutter, and means for exerting tension on said apron to move said platform with the severed material resting thereon to transfer the material so severed away from its native position.

13. A mining and loading machine comprising mechanism for dislodging a section of material from a mine vein, means for operating said dislodging mechanism, a device adjacent said dislodging mechanism and 70 having an upright roughened surface, and means cooperating with said upright roughened surface by moving the dislodged material against the same to assist in removing the dislodged material from the position 80 which it assumes after being dislodged.

14. In a mining machine, the combination with a cutter head, of an abutment carried by said cutter head and having a roughened outer surface, means mounted upon said cutter head for severing a section of material from a mine vein, and means for moving 85 said abutment while in contact with said severed material to move the latter away from its native position.

15. In a mining machine, the combination with a supporting frame, of a device having a roughened surface and mounted on said frame, means for dislodging material from a mine wall, and mechanism for forcing the 95 dislodged material from its native position against said roughened surface to break the dislodged material into pieces.

16. In a mining machine, a cutter-head, a curved plate carried by said cutter-head 100 and having a roughened outer surface, means for severing a section of material from a mine vein, and an apron arranged to enclose the severed material between one surface thereof and said plate to assist in 105 moving said material from its native position.

17. In a mining and loading machine, the combination with a device for severing a section of material from a mine vein, of 110 means for operating said device, movable mechanism opposite three sides of the cut material while still occupying its original position integral with the mine wall, and means for operating said movable mechanism to withdraw the cut material from the mine wall.

18. In a mining machine, a cutter-head having a cutter arranged to sever a section of material from the face of a mine vein, a plate having a roughened surface, mechanism for holding the material severed by said cutter against said surface, and means for moving said plate to transfer the severed material from its native position.

19. In a mining machine, a cutter-head, a cutter carried by said cutter-head and arranged to sever a section of material from a mine vein, a receiving plate, means for moving said receiving plate beneath the 130

severed material while the material remains in its native position, a movable friction plate arranged to contact with the material, and mechanism for moving said friction plate and receiving plate in unison with one another to transfer the material from its native position.

20. In a mining machine, a cutter, means for moving said cutter to sever a section of material from a mine vein, a receiving plate for the severed material, means for moving said receiving plate beneath said material while the material is in its native position, a friction plate arranged to engage the exposed surface of the severed material, an apron movable into the kerf formed by said cutter and arranged to hold the material on said receiving plate in contact with said friction plate, and means for moving said apron, receiving plate and friction plate to transfer the severed material away from its native position.

21. In a mining machine, a loop cutter, means for moving said cutter to sever a section of material from a mine vein, a receiving plate secured to said cutter and movable therewith beneath the material severed by said cutter while the material remains in its native position, an apron secured to said cutter and movable therewith into the kerf formed by said cutter at one side of the material being severed, a friction plate arranged to engage the exposed surface of the severed material, and means for moving said receiving plate, apron and friction plate to transfer the severed material away from its native position.

22. In a mining machine, a cutter-head, a cutter carried by said cutter-head and arranged to sever a section of material from a mine vein, a plate carried by said cutter-head and having a roughened surface, an apron, and means for exerting tension on said apron to force the material severed by said cutter into contact with said roughened surface and to move said material while thus held away from the position it occupied when severed.

23. In a mining machine, a cutter, means for moving said cutter to sever a section of material from a mine vein, a plate having a roughened surface, a receiving plate for the material severed by said cutter, means for moving the receiving plate beneath the severed material while the material remains in its native position, an apron, means for moving said apron into position to enclose the material severed by said cutter between said apron and said roughened plate, and means for exerting tension on said apron to hold the severed material into contact with said roughened plate and to move said material while thus held away from its native position.

24. In a mining machine, the combination

with cutting mechanism comprising a cutter head, of means for operating said cutting mechanism, projections mounted on said cutter head to form a roughened outer surface, and means for moving cut material against said roughened surface while returning said cutting mechanism to initial position to effect the removal of the cut material from the mine wall and the restoration of said cutting mechanism to initial position.

25. A mining machine comprising cutting mechanism having a cutter head, and a corrugated device movably mounted on said cutter head in position to be engaged by cut material and move relatively to said cutter head to guard the latter.

26. A mining machine comprising cutting mechanism having a cutter head, and a drum movably mounted on said cutter head and having an outer corrugated surface adapted to be engaged by cut material when removed from the mine wall and move with said cut material relatively to said cutter head to guard the latter.

27. In a mining machine, the combination with cutting mechanism comprising a cutter head, of a cylinder having a roughened outer surface and movably mounted on said cutter head, and a contact member carried by said cylinder and movable therewith to transfer material cut by said cutting mechanism.

28. In a mining machine, the combination with cutting mechanism comprising a cutter head, of a cylinder movably mounted on said cutter head and having a roughened outer surface, a contact member carried by said cylinder and projecting outwardly therefrom, and means for rotating said cylinder together with said contact member to transfer cut material away from its native position.

29. In a mining machine, the combination with mechanism for dislodging a section of material from a mine wall, of a receiver for the dislodged material, means for moving such receiver into position beneath said material, a contact member in position to engage an upright surface of a mass of dislodged material, and means for moving said contact member relatively to said receiver for sliding the dislodged material over said receiver away from the position it occupied when dislodged.

30. In a mining machine, the combination with a supporting frame, of core-cutting mechanism comprising a cutter-frame, and a device additional to the cutter-frame and extending horizontally back from the core-cutting mechanism to form a platform below the core tending to support the latter.

31. In a mining machine, a loop chain core cutter, means for operating said cutter to sever a section of material from a mine

vein, a receiver, means for moving said receiver into the kerf formed by said cutter and beneath the material severed thereby, a follower arranged to contact with the material severed by said cutter, and means for moving said follower and receiver together to transfer the severed material away from its native position.

32. In a mining machine, the combination with kerf-cutting mechanism for cutting spaced-apart kerfs and a communicating kerf back of a core of material in a mine wall, of means for operating such kerf-cutting mechanism to completely sever a core of material from a mine wall, a platform for supporting the core of material intact until after the entire core is completely severed from the mine wall, and means for operating said supporting platform to move back from the mine wall said core of material in its entirety.

33. In a mining machine, the combination with cutting mechanism, of means for operating said cutting mechanism to entirely cut out from a mine wall a section of material, a platform following said cutting mechanism to extend under a section of material as it is being cut in position for receiving the cut material from above, and means for operating said receiving platform to cause the same to carry into loading position the section of material resting freely by gravity thereon.

34. In a mining machine, a cutter arranged to sever a section of material from a mine vein, a receiver movable into position beneath the severed material, an apron movable into the kerf formed by said cutter at one side of the severed material, a follower for forcing the severed material away from its native position, and means for moving said receiver, apron and follower together to transfer the severed material.

35. In a mining machine, a loop cutter arranged to form a kerf having a substantially horizontal portion and an upright portion, a receiver movable into the horizontal portion of said kerf, an apron movable into the upright portion of said kerf, a contact member for forcing the severed material away from its native position, and means for moving said apron, receiver and contact member in unison with one another.

36. In a mining machine, the combination with mechanism for entirely cutting out a section of material from the wall of a mine, of means extending under the core in position to receive the severed section of material directly from its original position in the mine wall, and apparatus for moving said receiving means horizontally to carry the material thereon horizontally back from the mine wall toward loading position.

37. In a mining machine, the combination with loop chain core-cutting mechanism, of

a platform approximately in the plane of the lower run of said loop chain core-cutting mechanism in position for receiving the cut material from the mine wall, means for adjusting the height of said core-cutting mechanism and said platform while said platform is maintained approximately in the plane of the lower run of said core-cutting mechanism, means for operating said core-cutting mechanism to cut a plurality of cores across the mine wall one above another at the various heights to which said loop chain core-cutting mechanism is adjusted, and apparatus for moving said platform to cause the same to carry the material received thereby back from the mine wall.

38. In a mining machine, the combination with cutting mechanism, of means for operating said cutting mechanism to dislodge a section of material from a mine vein, a supporting frame for said cutting mechanism, a contact member movable relatively to said supporting frame, means for moving said contact member along the path of movement of said cutting mechanism to force material dislodged thereby away from its native position, a supporting plate movable beneath the material dislodged, and means for confining the dislodged material at the front and rear sides thereof.

39. In a mining machine, the combination with a supporting frame, of loop chain core-cutting mechanism carried thereby for swinging movement on an upright axis, a platform carried by said frame approximately in the plane of the lower run of said loop chain core-cutting mechanism in position for receiving material directly from the mine wall as dislodged by such cutting mechanism, said cutting mechanism and said platform being adjustable to various heights to enable said cutting mechanism to cut cores one above another, and means for operating said platform to cause the same to carry the dislodged material back from the mine wall.

40. In a mining machine, a loop cutter, means for rotating said cutter to sever a section of material from a mine vein, a contact member, means for rotating said contact member to force the material severed by said cutter away from its native position, a supporting plate arranged beneath said material during the movement thereof by said contact member, an apron arranged to enclose said material at one side thereof during said movement, and a guard wall arranged to enclose said material at the side thereof opposite said apron during said movement.

41. A mining machine comprising a supporting frame, loop chain core-cutting mechanism for entirely cutting out from a mine wall adjacent said frame a crescent-shaped core of material, means for operat-

ing said loop chain core-cutting mechanism, a platform connected to said frame for receiving all of said core directly from its cut position in the mine wall, and means for moving said platform together with the core thereon back from the mine wall.

42. In a mining machine, means for severing a section of material from its native bed, a rigid plate arranged to contact with one surface of the material so severed, a flexible member arranged to contact with another surface thereof, a plate for supporting said material, means for moving said supporting plate and flexible member in unison with one another to transfer said material from its native position, and a follower movable in the rear of said material during said transfer.

43. In a mining machine, a circular cutter-head, a loop cutter carried by said cutter-head and extending outwardly therefrom, a guard plate connected to said cutter-head and having a roughened external surface, a flexible apron carried by said cutter at the outer portion thereof and movable into the kerf formed thereby, and means for exerting tension on said apron to cause said apron to squeeze the material severed by said cutter into contact with said roughened surface.

44. In a mining machine, a cutter-head, a guard plate connected to said cutter-head and having a roughened outer surface, a loop cutter carried by said cutter-head and projecting outwardly therefrom, a flexible apron secured to said cutter at the outer portion thereof and movable into the kerf formed thereby, a receiving plate for the material severed by said cutter arranged to be moved into the kerf formed by said cutter beneath said material, and means for exerting tension on said apron to squeeze the material severed by said cutter and supported by said receiving plate into contact with said roughened surface.

45. In a mining machine, a cutter-head having a roughened outer surface, a loop cutter carried by said cutter-head and projecting outwardly therefrom, an apron, means for moving said apron into the kerf formed by the outer portion of said cutter, a receiving plate, means for moving said receiving plate into the kerf formed by said cutter beneath the material severed thereby, means for exerting tension on said apron to squeeze the material severed by said cutter and supported by said receiving plate into contact with said roughened surface, and means for moving said receiving plate, apron and cutter-head in unison with one another to transfer the material held thereby away from its native position.

46. In a mining machine, a cutter-head having a curved roughened outer surface, a loop cutter carried by said cutter-head and

projecting outwardly therefrom, a flexible apron, means for moving said apron into the kerf formed by said loop cutter, a receiving plate, means for moving said receiving plate into the kerf formed by said cutter beneath the material severed thereby, means for exerting tension on said apron to squeeze the material on said receiving plate into contact with the surface of said cutter-head and to rotate said cutter-head and receiving plate in unison with said apron to transfer the material severed thereby away from its native position, and a follower arranged to contact with said material in the rear thereof during said movement to assist in the transfer of said material.

47. The combination with a mining machine comprising a movable frame, of a supporting frame adapted to occupy a stationary position during the operation of said mining machine, a supplemental frame pivotally connected to the rear end of said movable frame and also pivotally connected to said supporting frame for adjustment relatively thereto, means for holding said supplemental frame in adjusted position relative to said supporting frame, and means intermediate the ends of said movable frame and co-acting with said supplemental frame for adjusting the position of said movable frame in an arc on a radius approximately equal to the length of said movable frame.

48. The combination with a mining machine comprising a movable frame, of a supporting frame adapted to occupy a stationary position in a mine chamber during the operation of said mining machine, a supplemental frame pivotally connected to said supporting frame for adjustment relatively thereto and also pivotally connected to the rear portion of said movable frame of said mining machine, said supplemental frame being adjustable relatively to said supporting frame to vary the elevation of the pivotal connection between said supplemental frame and the rear portion of said movable frame, and means for holding said supplemental frame in adjusted position on said supporting frame.

49. In a mining machine, the combination with a supporting base, of an arm pivotally carried by said base and extending rearwardly therefrom, means for holding said arm in adjusted position on said base, a mining machine frame, means comprising a pivotal connection between the rear end of said arm and the rear end of said mining machine frame for supporting said mining machine frame, and mechanism for adjusting the position of said mining machine frame on its pivotal connection to said arm.

50. In a mining machine, the combination with a frame, of cutting mechanism mounted at the forward end of said frame, means

- 5 pivotally connected to the rear end of said frame for supporting the latter, mechanism for adjusting the elevation of said pivotal support, and means associated with said adjusting mechanism for tilting said cutting mechanism up and down on a horizontal axis at said pivotal support to secure adjustment in elevation of said cutting mechanism along an arc having a radius approximately equal to the length of said frame, 70 said adjusting mechanism and tilting means assisting said pivotal support in supporting said frame and said cutting mechanism at adjusted elevation during the operation of said cutting mechanism.
- 10 51. In a mining machine, the combination with a supporting base, of a pair of rearwardly extending spaced-apart arms pivotally supported on said base, means for holding said arms in adjusted positions on said base, a mining machine frame pivotally connected to said arms, and means for adjusting the position of said mining machine frame about its pivotal connection to said arms.
- 20 52. In a mining machine, the combination with a supporting frame, of a supplemental frame mounted on said supporting frame for adjustment relatively thereto and comprising an arcuate rack and an arm rigid therewith, a mining machine frame pivotally connected at its rear end to the rear end of said arm, means for positively holding said supplemental frame in adjusted position relatively to said supporting frame by holding said supplemental frame rigidly connected to said supporting frame against movement relatively thereto in any direction, and means comprising a gear carried by said mining machine frame in position to mesh with said arcuate rack to adjust said mining machine frame about its pivotal connection with said arm to secure adjustment in elevation of the forward end of said mining machine on a radius approximately equal to the length of the mining machine frame.
- 30 53. In a mining machine, the combination with a supporting frame, of a supplemental frame comprising an upright arcuate rack and an arm rigidly secured to said rack and extending rearwardly therefrom, a pivotal connection between said supporting frame and said supplemental frame intermediate the ends of said upright arcuate rack, a mining machine frame pivotally connected at its rear end to the rear end of said arm, means at the lower end of said upright arcuate rack for holding said supplemental frame in adjusted position relative to said supporting frame by rigidly connecting said supplemental frame to said supporting frame and preventing relative movement in any direction, and mechanism comprising a gear carried by said mining machine frame in position to mesh with said arcuate rack to adjust the position of the forward end of said
- 35 mining machine frame about its pivotal connection to said arm on a radius approximately equal to the length of said mining machine frame.
- 40 54. In a mining and loading machine, the combination with a supporting frame, of cutting mechanism mounted thereon, a conveyer mounted on said frame for transferring material severed by said cutting mechanism, a plate extending over one run of said conveyer and adapted to support an operator, means for operating said cutting mechanism and said conveyer, and mechanism comprising controlling levers within the reach of said operator for controlling the 75 operation of said cutting mechanism and of said conveyer.
- 50 55. In a mining and loading machine, the combination with a supporting frame, of cutting mechanism mounted thereon, means comprising a conveyer for transferring dislodged material toward loading position, said conveyer having its opposite runs in the same horizontal plane, a plate extending over the return run of said conveyer and mechanism within reach of an operator on said plate for controlling said cutting mechanism and said transferring means.
- 60 56. In a mining and loading machine, the combination with a supporting frame, of mechanism mounted thereon for dislodging material from a mine wall, means for transferring the dislodged material along said frame toward loading position, said transferring means comprising a conveyer, and mechanism associated with said transferring means and inclined toward the operating portion of said conveyer to receive from said transferring means the dislodged material and direct it onto said operating portion of 90 said conveyer.
- 70 57. In a mining machine, the combination with a supporting frame, of upright loop chain core-cutting mechanism mounted thereon for arcuate feeding movement relatively thereto on an upright axis, means for operating said core-cutting mechanism including swinging feeding movement thereof on such upright axis, means on said frame adjacent said core-cutting mechanism 100 in position to receive cuttings therefrom, a conveyor for transferring said cuttings toward loading position, an extension for said frame to close the gap between said frame and the face of the mine wall to assure the transfer of said cuttings from the mine wall to said conveyer, and mechanism connected to such extension in spaced-apart positions to secure equalized rectilinear forward and rearward movement of such extension relatively to said frame.
- 80 58. In a mining and loading machine, the combination with a supporting frame, of core-cutting mechanism mounted thereon, a conveyer mounted on said frame, an exten- 110
- 90
- 100
- 110
- 120
- 130

5. In a mining machine, the combination for said frame to close the gap between said frame and the base, of the mine wall to assure the passage of cuttings from said core-cutting mechanism to said conveyer, and means comprising spaced-apart rack and pinion mechanism for securing rectilinear forward and rearward movement of said extension relatively to said frame.
6. In a mining machine, the combination with a frame comprising a bed plate, of a chain core-cutter mounted on said frame, a trough on said bed plate adjacent the emerging run of the chain cutter, a conveyer movable along said trough to transfer the cuttings received by said trough automatically from said chain cutter, and a gear operated extension plate for closing the gap at the mine wall and preventing the escape of such cuttings.
7. In a mining machine, the combination with a frame comprising a bed plate, of a chain core-cutter arranged to discharge the cuttings formed thereby onto said bed plate, a conveyer in position on said bed plate to transfer toward loading positions the cuttings from the positions where deposited by said core-cutter, apparatus for transferring the cut core material through said conveyer for transfer by the latter toward loading position, and a double geared extension plate to prevent escape of the cuttings at the mine wall.
8. In a mining machine, a frame comprising a lateral bed plate, a conveyor having flights movable over the surface of said bed plate, an upright chain core cutter arranged to discharge the cuttings formed thereby onto the forward end of said bed plate, and a rib extending upwardly from said bed plate adjacent the path of movement of said flights and the forward end of said conveyor to prevent escape of the cuttings formed by said chain out of the path of movement of said flights.
9. In a mining machine, the combination with cutting mechanism comprising a frame, of a plate, a hinged connection between said plate and said frame, and means for operating said cutting mechanism including feeding movement thereof while moving said plate into position beneath the cut material.
10. In a mining machine, a loop cutter, a plate secured to the lower portion of said cutter and movable into the kerf formed thereby, and a hinged connection between said cutter and said plate.
11. In a mining machine, a loop cutter, means for rotating said cutter about an upright axis, an arcuate plate secured to the lower portion of said cutter and movable therewith into the kerf formed thereby, and a hinged connection between said cutter and said plate.
12. In a mining machine, a cutter-head movable in an arcuate path, a base plate on which said head is mounted, a cutter carried by said head and rotatable on said base plate, an arcuate receiver plate secured to said cutter and movable therewith beneath the material severed thereby, and a hinged connection between said cutter and said receiver plate.
13. In a mining and loading machine, the combination with a supporting frame, of cutting mechanism mounted thereon, means for operating said cutting mechanism including feeding movement thereof relatively to said supporting frame, a movable plate for receiving material severed by said cutting mechanism, and a deflector movably mounted on said frame to permit movement of said plate relatively to said frame in a direction to transfer material from the mine wall toward loading position and arranged to deflect material from said plate during such movement thereof.
14. A mining and loading machine comprising a supporting frame, means mounted thereon for severing material from a mine wall, a conveyer for transferring dislodged material toward loading position, a plate for receiving dislodged material from said severing means and transferring it to said conveyer, and means arranged to intercept the movement of material with said plate beyond a predetermined position but permitting the plate to be moved past said conveyer.
15. A mining and loading machine comprising a supporting frame, means mounted thereon for severing material from a mine vein, a conveyer mounted on said frame in position to transfer material toward loading position, means for moving said plate to transfer material thereon to said conveyer, a slideway on said frame for said plate, and a stop arranged to close said slideway against movement of the material beyond a predetermined position relative to said conveyer but permitting said plate to move past said predetermined position.
16. A mining and loading machine comprising a supporting frame, a mechanism mounted thereon for dislodging material from a mine wall, a conveyer having an operating run extending toward loading position, a plate for receiving the material from said dislodging mechanism, a slideway on said frame in which said plate is arranged to move, and a pivoted stop for closing said slideway adjacent the operating run of said conveyer to prevent the material from moving past the operating run of said conveyer but permitting said plate to move beyond said operating run.
17. In a mining machine, the combination with cutting mechanism, of means for operating said cutting mechanism including arcuate feed thereof on an upright axis, an arcuate plate movable with said cutting

mechanism in position to receive material severed thereby, means for moving said plate in the reverse direction to carry the material thereon away from the mine wall, 5 and a device arranged to permit such reverse movement of said plate but blocking the movement of material carried thereby beyond a predetermined position.

71. In a mining machine, the combination with a supporting frame, of a loop chain core-cutter having an unobstructed core-opening and mounted on said frame for arcuate feeding movement on an upright axis, means for rotating said core-cutter, 10 said rotating means comprising a pair of cooperating gears, one being mounted for rotation on the axis of said core-cutter, and releasable means for holding the concentric gear stationary during the rotation of the other to cause rotation of said core-cutter, 15 said last-named means being releasable to permit rotation of said core-cutter independently of said gears.

72. In a mining machine, a cutter-head, 25 means for rotating said cutter-head comprising a rack, a pinion arranged to mesh with said rack, gearing for driving said pinion, and means for holding said rack stationary to cause the rotation of said cutter-head, 30 said holding means being releasable to permit rotation of said cutter-head independently of said gearing.

73. In a mining machine, a frame, a shaft carried by said frame, a cutter-head rotatably mounted on said shaft, a gear secured to said shaft, gearing carried by said cutter-head arranged to mesh with the gear on said shaft, means for holding said shaft stationary, means for driving the gearing 35 on said cutter-head to cause said cutter-head to rotate about said shaft, and means for releasing said holding means to permit rotation of said cutter-head independently of said gearing.

74. In a mining machine, a frame, a shaft carried by said frame, a cutter-head mounted on said frame and arranged to rotate about said shaft, a gear secured to said shaft, gearing carried by said cutter-head comprising 50 a worm drive, and meshing with the gear on said shaft, means for holding said shaft stationary to cause rotation of said cutter-head when the gearing carried thereby is operated, said holding means being releasable to permit rotation of said cutter-head independently of said gearing.

75. In a mining and loading machine, the combination with a supporting frame, of a core-cutting mechanism mounted thereon 55 and having an upper run horizontal in elevation, means for operating said core-cutting mechanism including arcuate feeding movement thereof relatively to said supporting frame, means mounted on said frame in position to extend under the core cut by said

cutting mechanism to receive a core and move it from the mine wall, and means for adjustably supporting said frame in elevated position with the upper run of said core-cutting mechanism in position to cut 70 a kerf in the plane of the roof of the mine chamber.

76. In a mining machine, the combination with a loop chain core-cutter having an upper run straight in elevation, of means 75 for operating said loop chain core-cutter including the feed thereof, framework for supporting said core-cutter at various elevations, and means for adjustably supporting said framework to cause said core-cutter to 80 cut a kerf at the roof in continuation of the plane of the roof of the mine chamber.

77. In a mining and loading machine, the combination with a loop chain core-cutter having an upper run straight in elevation, of 85 means for operating said loop chain core-cutter including feed thereof arcuately on an upright axis, framework for supporting said core-cutter for operation at various elevations, and means for adjusting the position of said framework to support the core-cutter so that its upper run will cut a kerf 90 approximately in the plane of the roof of the mine chamber.

78. In a mining and loading machine, the 95 combination with a chain cutter, of means for operating said chain cutter to sever a section of material from a mine vein by forming a kerf in said material, a conveyer, means for supporting said chain cutter in such position as to cause the same to discharge its 100 cuttings into the path of movement of said conveyer, means for moving the material severed by said chain cutter into position to be transferred by said conveyer toward loading position, and means for controlling the movement of said conveyer at the will of the operator.

79. The combination with a mining machine, of a main supporting frame, a supplemental frame pivotally connected to said main frame, means for rigidly holding said supplemental frame in adjusted position relative to said main frame, a pivotal connection between the rear end of said mining machine and the rear end of said supplemental frame, and means connected between an intermediate part of said mining machine and the forward end of said supplemental frame for effecting the support of said mining machine at various elevations and at 110 various inclinations.

80. The combination with a mining machine, of a pair of arms pivoted to the rear portion of said mining machine, one on one side thereof, and the other on the opposite side thereof, a main frame for pivotally supporting said arms on a horizontal axis, and mechanism connected between an intermediate portion of said mining machine and 115 120 125 130

said arms for varying the inclination of said mining machine.

81. The combination with a mining machine, of framework comprising spaced apart arms pivoted to said mining machine on opposite sides thereof, a pair of roof jacks for holding said framework in stationary position while providing a free and unobstructed space for up and down tilting movement of said mining machine, and mechanism connected between said mining machine and said arms for tilting said mining machine on its pivotal connections to said arms. 70

82. The combination with a mining machine, of framework comprising a main frame and a pair of spaced-apart arms pivotally connected to said main frame and extending rearwardly to pivotal connections between said arms and said mining machine on opposite sides of the latter, means for rigidly holding said arms to said main frame in adjusted positions, and mechanism connected between the forward portions of said arms and said mining machine intermediate 85 the ends of the latter to vary the inclination of said mining machine on its pivotal connections with said arms. 90

83. The combination with a mining machine, of a pair of arms connected at their rear ends to the rear end of said mining machine on opposite sides thereof, a main frame for pivotally supporting said pair of arms while the latter extend rearwardly from said main frame and while said mining machine extends forwardly from the pivotal connection between the rear ends of said arms, and means for rigidly holding said arms in adjusted position on said main frame for holding the mining machine at various inclinations and the forward portion of said mining machine at various elevations. 95

84. The combination with a mining machine, of supporting framework to which said mining machine is pivotally connected, spaced-apart ceiling jacks on opposite sides of said mining machine for holding said framework stationary, and mechanism connected between said mining machine and said framework for varying the inclination of said mining machine on its pivotal connection with said framework and for holding the mining machine rigidly in adjusted position against movement up or down relatively to said framework during the operation of said mining machine. 105

85. The combination with a mining machine, of a main frame, spaced apart roof jacks on opposite sides of said mining machine for holding said main frame stationary, spaced apart arms pivotally connected to said frame and extending rearwardly to pivotal connections to the rear end portion of said mining machine, means for holding said arms in adjusted positions on their pivotal connections to said main frame, and

mechanism connected between an intermediate portion of said mining machine and said arms for lifting and lowering the forward portion of said mining machine on its rear pivotal connections to said arms. 70

86. In a mining machine, the combination with core cutting mechanism having an unobstructed core opening therethrough, of means for operating said core cutting mechanism, an upright abutment having an outer friction surface, means for moving core material from the mine wall against said upright friction surface, and mechanism for moving said abutment to continue the movement of said core material from the mine wall toward loading position. 75

87. In a mining machine, the combination with core-cutting mechanism for cutting a core in one operation along a mine wall, of means for operating the same, receiving means, movable with said core-cutting mechanism beneath the core cut by the latter, a movable friction device engaged by the core, and apparatus for moving the said friction device and said receiving means in unison with each other to transfer the cut core from its native position toward loading position. 85

88. In a mining machine, the combination with a receiving plate, of means for moving said receiving plate beneath cut material while the latter retains its native position, a movable friction device, and means for moving the said material into contact with said friction device and moving said plate with the material thereon toward loading position. 95

89. In a mining machine, the combination with loop chain core-cutting mechanism having an unobstructed core-opening therethrough, of a receiving device extending rearwardly from the lower run of said core-cutting mechanism and movable bodily therewith, means for adjustably supporting said loop chain core-cutting mechanism and said receiving device at various elevations, and mechanism for operating said core-cutting mechanism including lateral feed thereof at various elevations to cut a plurality of cores one above another. 105

90. In a mining machine, the combination with a loop chain cutter, of mechanism for operating the same to entirely sever from the mine wall a crescent-shaped section of material, a segmental platform following said loop chain cutter and movable therewith to receive the said crescent-shaped section of material, and means for moving said segmental platform to cause the same to carry said section of material back from the mine wall. 110

91. In a mining machine, the combination with a main frame, of a supplemental frame rotatably mounted on said main frame, cutting mechanism carried by said supplemental frame. 130

tal frame, means for operating said cutting mechanism, a platform carried by said supplemental frame for receiving the material cut from a mine wall by said cutting mechanism, and means for moving said supplemental frame to cause said platform to carry the cut material back from the mine wall.

92. In a mining machine, the combination 10 with loop chain core-cutting mechanism having an unobstructed core-opening therethrough, of means for operating said core-cutting mechanism including lateral arcuate feeding movement thereof on an upright 15 axis, and a hollow cylindrical drum for enclosing and guarding said operating means.

93. In a mining machine, the combination 20 with cutting mechanism, of means for operating the same, a rotatable cylinder surrounding said operating means, mechanism for holding said cylinder from rotation during the forward feed of said cutting mechanism, and means for moving cut material against the outer surface of said drum and 25 for rotating said drum while restoring said cutting mechanism toward initial position.

94. In a mining machine, the combination 30 with a supporting frame, of a supplemental frame mounted thereon, cutting mechanism mounted on said supplemental frame, a cylinder rotatably mounted on said supplemental frame and having a corrugated outer surface, and means for operating said cutting mechanism including feed of said supplemental frame.

95. In a mining machine, the combination 40 with a supporting frame, of cutting mechanism mounted on said frame, means for operating said cutting mechanism, an adjustable extension at the forward end of said supporting frame in position to close the gap between the forward end of said supporting frame and the upright mine wall on which said cutting mechanism is adapted 45 to operate, and means comprising spaced-apart engaging devices between said supporting frame and said extension to move said extension relatively to said frame to adjust the position of said extension.

96. In a mining machine, the combination 50 with a main frame, of a supplemental frame rotatably mounted on said main frame, a loop chain cutter, a motor mounted on said supplemental frame, operating connections 55 between said motor and said loop chain cutter, a platform mounted on said supplemental frame to follow said loop chain cutter and move therewith to receive the material cut from a mine wall by said loop chain cutter, and means for moving said platform to cause the same to carry the severed section of material back from the mine wall.

97. In a mining machine, the combination 60 65 with a main frame, of a supplemental frame

rotatably mounted on said main frame, a loop chain cutter carried by said supplemental frame, means carried by said supplemental frame for operating said chain cutter to sever a section of material from the mine wall, a segmental extension of said supplemental frame to form a platform to receive and support the severed section of material, and means for moving said platform to carry said section of material back 70 75 from the mine wall.

98. In a mining machine, the combination 80 with a supporting frame, of loop chain core-cutting mechanism having an unobstructed core-opening therethrough and mounted for lateral movement on said supporting frame, means for operating said loop chain core-cutting mechanism including lateral feed thereof relatively to said supporting frame and across a mine wall to cut a core of material in one feeding operation, receiving mechanism following said core-cutting mechanism approximately in the plane of the lower run thereof so as to extend under the core of material, and means for operating 85 90 said receiving mechanism to carry the cut material of said core thereon back from the mine wall toward loading position.

99. In a mining machine, the combination 95 with a frame, of loop chain core-cutting mechanism mounted thereon, means for operating said loop chain core-cutting mechanism to cut a core in a mine wall in one feeding operation in a general horizontal direction across said mine wall, a platform 100 extending rearwardly from said loop chain core-cutting mechanism and movable bodily therewith in position for receiving cut material immediately as dislodged, and mechanism for effecting the transfer of such dislodged material toward loading position.

100. In a mining machine, the combination 110 with a supporting frame having a platform with its forward edge arcuate to approximately fit an arcuate mine wall, of loop chain core-cutting mechanism mounted on said frame for swinging feeding movement relatively thereto on an upright axis, means for operating said loop chain core-cutting mechanism, mechanism for adjusting the elevation of said core-cutting mechanism, an extension plate at the forward end of said platform adjustable to positions to fill the gap between the forward end of said platform and the mine wall at various elevations of said core-cutting mechanism, and means comprising spaced-apart rack and pinion devices between said frame and said extension plate to move the latter rectilinearly and relatively to said frame to adjust the position of said extension plate between the forward end of said platform and the upright arcuate mine wall.

101. In a mining and loading machine, 115 the combination with cutting mechanism, of

means for operating the same, a plate for receiving dislodged material directly from said cutting mechanism, a conveyer, and means for moving said plate under said conveyer to effect delivery of said material to said conveyer.

102. In a mining and loading machine, the combination with core cutting mechanism mounted for arcuate movement on an upright axis, of means for operating said core cutting mechanism including arcuate feed thereof, an arcuate platform movable beneath the core of material cut by said cutting mechanism to receive the dislodged material directly from its cut position at the mine wall, a conveyer, and means for moving said arcuate platform under said conveyer to cause the latter to remove the material gradually from said platform and transfer said material toward loading position.

103. In a mining and loading machine, the combination with a receiving platform, of means for dislodging material from a mine wall onto said platform, a flight conveyer, and means for moving said platform under said flight conveyer to cause the flights of said conveyer to move over the upper surface of said platform and transfer material therefrom toward loading position.

104. In a mining and loading machine, the combination with a receiving platform, of means for dislodging material from a mine wall onto said platform, a conveyer, a passageway under said conveyer and transversely thereof for said platform, and a movable device in said passageway for obstructing movement of material therethrough but permitting movement of said platform through said passage.

105. In a mining and loading machine, the combination with core cutting mechanism mounted for arcuate movement on an upright axis, of means for operating said cutting mechanism including arcuate feed thereof, an arcuate platform connected to said cutting mechanism and following the same to receive dislodged material, a conveyer radiating from said upright axis and extending around the same, an arcuate passageway extending transversely under said conveyer, a pivoted shield for obstructing the movement of material through said passageway but permitting free movement of said platform, and means for moving said platform under said conveyer to cause the latter to remove material from said platform and transfer such material toward loading position.

106. In a mining and loading machine, the combination with core-cutting mechanism, of means for operating the same, a platform following said cutting mechanism in position to receive the material as it is

dislodged, a loading conveyer, and means for effecting the delivery of material from said platform to said conveyer.

107. In a mining and loading machine, the combination with loop chain core-cutting mechanism, of a frame for supporting said core-cutting mechanism for arcuate feeding movement on an upright axis, means for operating said cutting mechanism including arcuate feeding movement thereof relatively to said frame, means following said core-cutting mechanism in position to receive the material as dislodged, a loading traveling conveyer, and mechanism for effecting the delivery of material from said receiving means to said conveyer.

108. In combination, a cutter head, a loop core-cutter carried by said head for movement about an upright axis, a table movable in the kerf formed by said loop core-cutter, and means for operating said table to remove portions of material severed by said cutter during the operation of said cutter.

109. In a mining machine, the combination with a frame comprising a platform, of core-cutting mechanism having an unobstructed core-opening therethrough and mounted on said frame, means for operating said core-cutting mechanism to effect the dislodgment of material from its native bed in a mine, and mechanism following closely behind said core-cutting mechanism in position to extend under the cut core material to receive and carry the latter by gravity on said platform toward loading position.

110. In a mining machine, the combination with a supporting frame, of a rotary supplemental frame mounted on said supporting frame for arcuate movement through an angle of 180 degrees or more, cutting mechanism mounted on said supplemental frame and movable bodily therewith, means for operating said cutting mechanism including arcuate movement of said supplemental frame relatively to said supporting frame to effect arcuate feeding movement of said cutting mechanism, and a plane table on said supplemental frame in position to receive the cut material from said cutting mechanism.

111. In a mining machine, the combination with a supporting frame, of a supplemental frame rotatably mounted on said supporting frame for arcuate movement relatively thereto on an upright axis, core-cutting mechanism having an unobstructed core-opening therethrough and movable bodily with said supplemental frame through an arc on said upright axis, means for operating said core-cutting mechanism including movement of said supplemental frame to secure arcuate feeding movement of said core-cutting mechanism on said axis, and a table on said supplemental frame movable in a general horizontal direc-

tion with said core-cutting mechanism in position for receiving material severed thereby.

112. In a mining machine, a rotary cutter head, a loop cutter carried by said cutter head for severing material from the mine wall, and an arcuate table secured to the rear of said cutter and movable horizontally into the kerf formed thereby for receiving the material severed by said cutter.

113. In a mining and loading machine, the combination with kerf-cutting mechanism mounted for feeding movement in an arc about an upright axis, means for operating said kerf-cutting mechanism including arcuate feeding movement about said upright axis, and a device also movable in an arc about such upright axis for receiving the material and carrying the same toward loading position.

114. In a mining and loading machine, the combination with a main frame, of a supplemental frame mounted for arcuate movement on an upright axis on said main frame through an angle of 180° or more relatively to said main frame, kerf-cutting mechanism carried by said supplemental frame, means for operating said kerf-cutting mechanism including arcuate feed thereof on such upright axis and through such angle, and a loading device carried by said supplemental frame and movable therewith in an arc on said upright axis for receiving the dislodged material directly from its native position in the mine wall and carrying such material toward loading position.

115. In combination, a mining machine rotatable about an upright axis, a loop cutter extending radially from said mining machine and secured thereto for rotation therewith, and an arcuate table secured to said mining machine and movable with said loop cutter into the kerf formed by the lower portion thereof for receiving the material severed by said cutter and for transferring said material to a loading position.

116. In combination, a mining machine rotatable about a central upright axis, a loop cutter secured to said mining machine and rotatable therewith and arranged to sever material from a mine wall at any angular position relative to the axis of said machine, and a table carried by said machine and rotatable therewith for transferring the material severed by said cutter in any angular position thereof from its severed position to a position to be loaded.

117. In a mining and loading machine, the combination with a supporting frame, of a mining machine mounted on said frame for arcuate movement about an upright axis, said mining machine comprising core-cutting mechanism having an unobstructed core-opening therethrough, and a table

connected to said mining machine and movable in an arc therewith for transferring material dislodged by said core-cutting mechanism toward loading position.

118. A mining and loading machine comprising a main frame, of a supplemental frame having a platform for receiving dislodged material directly from a mine wall, mechanism mounted on said supplemental frame for cutting a single core of material in the mine wall by producing a continuous kerf therein entering and emerging from the mine wall at spaced-apart locations, said cutting mechanism having an unobstructed core-opening therethrough, means for operating said cutting mechanism including feeding movement thereof, means for operating said platform relatively to said main frame for carrying the dislodged material from the mine wall toward loading position, and means for adjusting the elevation of said platform for varying the position thereof in accordance with the height of the cut material.

119. A mining and loading machine comprising cutting mechanism to cut simultaneously a pair of separated kerfs and a back kerf connecting said separated kerfs, means for operating said cutting mechanism including the feed thereof during actuation to cut a column of material in its native bed, a platform in position for receiving material cut by said cutting mechanism, and means for operating said platform while the material rests thereon by gravity to carry such material from the mine wall toward loading position.

120. A mining and loading machine comprising a supporting frame, loop chain core-cutting mechanism mounted thereon for cutting a single core of material in a mine wall and leaving it substantially in the space occupied thereby, and means mounted on said frame and extending therefrom in position for insertion under the material irrespective of its elevation within predetermined limits to receive such material and carry it back from the mine wall.

121. A mining and loading machine comprising a main frame, a supplemental frame pivoted on said main frame on an upright axis, a loop chain cutter having an unobstructed opening therethrough and mounted on said supplemental frame, means for operating said cutter including the feed thereof to cut a column of material in the unmined mass, a platform on said supplemental frame, and means for operating said platform to carry the material of said column toward loading position.

122. A mining and loading machine comprising a supporting frame, cutting mechanism mounted on said frame and having an unobstructed opening therethrough, means for operating said cutting mechanism in-

cluding feed thereof through an arc to cut a column of material in the unmined mass adjacent said frame, and loading apparatus mounted on said frame and comprising a 5 platform for receiving the dislodged material directly from the mine wall in a plane below the mass of the cut column and carrying the dislodged material toward loading position while resting on said platform by 10 gravity.

123. In a mining machine, the combination with supporting framework, of core-cutting mechanism having an unobstructed core-opening therethrough and mounted on 15 said framework to swing on an upright axis, means mounted on said framework and movable relatively thereto in position to move under the cut core and receive the same, said receiving means being capable 20 of carrying the dislodged material away from the mine wall toward loading position when said receiving means is moved relatively to said framework, and means for operating said core-cutting mechanism including 25 arcuate feeding movement thereof by swinging the same on said upright axis relatively to said framework.

124. In a mining machine, the combination with supporting framework, of core-cutting mechanism mounted thereon and having an unobstructed core-opening therethrough, a platform mounted on said framework and movable relatively thereto under the core of cut material in position to receive 30 the severed section directly from its original position in the mine wall and carry the dislodged material thereon away from the mine wall when said receiving platform is moved relatively to said framework away from the mine wall, and means for operating said core-cutting mechanism including the feed thereof.

125. In a mining machine, the combination with a supporting frame, of loop chain 45 core-cutting mechanism having an unobstructed core-opening therethrough and mounted for lateral movement on said supporting frame, means for operating said loop chain core-cutting mechanism including 50 lateral feed thereof relatively to said supporting frame and across a mine wall to cut a core of material in one feeding operation, means extending in a general horizontal direction behind the lower run of 55 the core-cutting mechanism in position to receive dislodged material, said receiving means being movable laterally with said core-cutting mechanism, and means for moving said receiving means into receiving 60 position.

126. A mining machine comprising a supporting frame, loop chain core-cutting mechanism mounted on said frame for swinging feeding movement upon an upright axis, means for operating said loop 65

chain core-cutting mechanism, a support connected to said frame for receiving all of said core directly from its cut position in a mine wall, and means for moving said support together with the core thereon back 70 from the mine wall.

127. In a mining machine, the combination with a supporting frame, of a loop chain core-cutter having an unobstructed core leading therethrough and mounted on 75 said frame for swinging feeding movement relatively to said frame, means for operating said loop chain core-cutter, a supporting plate adapted to occupy a position extending in a general horizontal direction 80 and to move under the core to support and carry the same, and means for moving said plate to move the core thereon back from the mine wall.

128. In combination, a mining machine 85 frame, a cutter head carried by said frame, a loop core cutter carried by said cutter head for rotation about an upright axis, an arcuate table of less extent angularly than the angular rotation of said cutter during 90 a cutting operation, and means for operating said table to remove the material severed by said cutter a part at a time.

129. In combination, a mining machine frame, a cutter head having a loop core 95 cutter carried by said frame, an arcuate carrier having an angular extension of less than one hundred eighty degrees, and means for moving said carrier into the kerf formed by said loop cutter to receive a load of 100 material.

130. In combination, a mining machine frame, a cutter head carried by said frame, core-cutting mechanism carried by said cutter head, means for receiving material disconnected by said severing mechanism, said receiving means being arranged to transport 105 said material while said means remains in receiving position.

131. In combination, a mining machine 110 frame, a cutter head carried by said frame for rotation about an upright axis, a loop core-cutter carried by said cutter head, an arcuate table carried by said cutter head and having its forward end positioned adjacent the rear portion of said loop cutter, and means for imparting a reciprocatory movement to said table relative to said cutter head to transfer material received on 115 said table.

132. In a mining machine, the combination with a supporting frame, of means for pivotally supporting the rear portion of said supporting frame, mechanism for adjusting the elevation of said pivotal support, kerf cutting mechanism mounted on the forward portion of said supporting frame for arcuate movement relatively thereto on an upright axis for operation along the roof of a mine chamber approximately in continua- 120 125 130 135

- tion of the plane of such roof while the space above said supporting frame forward of said pivotal support remains free and unobstructed, and means extending downwardly from the lower side of said supporting frame for adjusting the elevation of the forward portion of said supporting frame together with the kerf-cutting mechanism mounted thereon.
133. In a mining machine, the combination with kerf-cutting mechanism, of a frame for supporting the same, a table mounted on said frame in position for movement into the kerf formed by said kerf-cutting mechanism, and means for operating said table by moving the same relatively to said frame, to remove material dislodged from the mine wall onto said table above the said kerf.
134. In a mining machine, the combination with a supporting frame, of kerf-cutting mechanism mounted thereon, a table mounted on said frame in position to enter the kerf cut by said kerf-cutting mechanism, and means for reciprocating said table in its entirety and back of the kerf-cutting mechanism to transfer dislodged material away from its cut position.
135. In a mining machine, the combination with a supporting frame, of kerf-cutting mechanism mounted thereon for arcuate feeding movement, an arcuate table mounted on said supporting frame for movement into the kerf cut by said kerf-cutting mechanism, and means for reciprocating said arcuate table to effect movement of the dislodged material from its cut position.
136. In a mining machine, the combination with a supporting frame, of kerf-cutting mechanism mounted thereon for arcuate movement on an upright axis, an arcuate table mounted on said frame for arcuate movement about said upright axis into the kerf cut by said kerf-cutting mechanism and into receiving position immediately back of said kerf-cutting mechanism while the latter remains in the plane of said kerf, and means for operating said table back of said kerf-cutting mechanism to transport cut material rearwardly from said kerf-cutting mechanism and away from its cut position.
137. In a mining and loading machine, the combination with a chain cutter, of means for operating said chain cutter to sever a section of material from a mine vein by forming a kerf in said material, a conveyer, means for supporting said chain cutter in such position as to cause the same to discharge its cuttings into the path of movement of said conveyer, means for moving the material severed by said chain cutter into position to be transferred by said conveyer toward loading position, and means for controlling the movement of said conveyer at the will of the operator.
138. In a mining and loading machine, the combination with core-cutting mechanism, of means for operating the same, a platform following said cutting mechanism in position to receive the material as it is discharged, a loading conveyer, and means for effecting the delivery of material from said platform to said conveyer.
139. In a mining and loading machine, the combination with loop chain core-cutting mechanism, of a frame for supporting said core-cutting mechanism for arcuate feeding movement on an upright axis, means for operating said cutting mechanism including arcuate feeding movement thereof relatively to said frame, means following said core-cutting mechanism in position to receive the material as dislodged, a loading traveling conveyer, and mechanism for effecting the delivery of material from said receiving means to said conveyer.
140. In a mining machine, the combination with cutting mechanism, of a support for the dislodged material, a main support for said cutting mechanism and for said first-named support, means for moving said first-named support in an arc concentric with the feed of said cutting mechanism and following the latter in such arcuate path, and means for guiding said cutting mechanism and said first-named support as a whole in an arc on said main support when the height of the cutting mechanism is adjusted.
141. In a mining machine, the combination with a main frame, of a supplemental frame mounted on said main frame for movement to various elevations, cutting mechanism mounted on said supplemental frame for movement in an arc in a general horizontal direction relatively to said supplemental frame to sever a section from the wall of a mine, and a support for the severed section in its entirety following said cutting mechanism and bodily movable therewith to extend under the severed section.
142. In a mining machine, the combination with a frame, of core-cutting mechanism mounted thereon, of means for operating said core-cutting mechanism to cut a core in a mine wall in one operation in a general horizontal direction across said mine wall, a platform following and moving with said core-cutting mechanism for receiving material cut from the mine wall by said cutting mechanism as soon as dislodged, and means mounted on said frame for moving said platform relatively to said frame to cause the same to carry the dislodged material back from the mine wall.
143. A mining machine comprising a supporting frame, cutting mechanism mounted thereon, a segmental platform for receiving the material cut by said cutting mecha-

nism, and means for moving said platform to the rear portion of said frame spaced from the mine wall, to carry the dislodged material from the mine wall to the rear end 5 of said frame.

144. The combination with core-cutting mechanism, of a platform following the same and movable therewith to receive the core of material cut from the mine wall by 10 said core-cutting mechanism, and means for simultaneously restoring said cutting mechanism to initial position preparatory to another cut and moving said platform to cause the same to carry the core of material 15 intact back from the mine wall.

145. In a mining machine, the combination with a supporting frame, of loop chain core-cutting mechanism mounted on said frame for feeding movement relatively 20 thereto, means for operating said loop chain core-cutting mechanism, a platform conforming to the contour of the unmined mass for receiving material as it is severed from its native position, and means for moving said platform relatively to said supporting frame to carry said dislodged material away from the mine wall toward loading position.

146. In a mining machine, the combination with supporting framework comprising 30 a loading platform at its rear portion, of cutting mechanism mounted on said framework for swinging feeding movement on an upright axis, arcuate receiving mechanism 35 movable under the cut material to receive and carry the same, and means for arcuately

and rearwardly moving said arcuate receiving mechanism to deliver the cut material to a position for movement onto said loading position. ⁴⁰

147. In a mining machine, the combination with supporting framework, of core-cutting mechanism having an unobstructed core-opening therethrough and mounted on said frame work to swing on an upright 45 axis, means mounted on said frame work and movable relatively thereto in position to move under the cut core and receive the same, said receiving means being capable of carrying the dislodged material away 50 from the mine wall toward loading position when said receiving means is moved relatively to said framework, and means for operating said core-cutting mechanism including arcuate feeding movement there- 55 of by swinging the same on said upright axis relatively to said framework.

148. A mining and loading machine comprising a supporting frame, core-cutting mechanism mounted thereon, means for 60 operating said core-cutting mechanism including arcuate feeding movement thereof relatively to said supporting frame, and means mounted on said frame in position to extend under the core cut by said cutting 65 mechanism to receive the core and move it from the mine wall.

In testimony whereof I have signed my name to this specification on this 17th day of May, A. D. 1916.

EDMUND C. MORGAN.
